(57) **CLAIM**

The ornamental design for a plant growth system suite, as shown and described.

DESCRIPTION

FIG. 1 is a first perspective view of a plant growth system suite showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The broken lines shown in the drawings depict portions of the plant growth system suite that form no part of the claimed design.

1 Claim, 10 Drawing Sheets
